(57) **CLAIM**

The ornamental design for a socket cover plate, as shown and described.

DESCRIPTION

FIG. 1 is a top view of a socket cover plate showing the new design;

FIG. 2 is a front view of the invention illustrated in FIG. 1, a rear view being identical;

FIG. 3 is a bottom view of the invention illustrated in FIG. 1;

FIG. 4 is a right side view of the invention illustrated in FIG. 1, a left side view being identical; and,

FIG. 5 is a perspective view of the invention illustrated in FIG. 1.

The broken lines in the drawings depict portions of the socket cover plate that form no part of the claimed design. The socket cover plate is shown with a symbolic break in its length. The appearance of any portion of the article between the break lines forms no part of the claimed design.

1 Claim, 5 Drawing Sheets
